UNITED STATES PATENT OFFICE.

ENOCH GEORGE, JR., OF PITTSBURGH, PENNSYLVANIA, ASSIGNOR TO THE McCONWAY & TORLEY COMPANY, OF PITTSBURGH, PENNSYLVANIA, A CORPORATION OF PENNSYLVANIA.

COUPLING OPERATING MECHANISM.

1,417,598.

Specification of Letters Patent. Patented May 30, 1922.

Application filed October 18, 1920. Serial No. 417,799.

To all whom it may concern:

Be it known that I, ENOCH GEORGE, Jr., a citizen of the United States, residing at Pittsburgh, in the county of Allegheny and State of Pennsylvania, have invented certain new and useful Improvements in Coupling Operating Mechanism; and I do hereby declare the following to be a full, clear, and exact description of the invention, such as will enable others skilled in the art to which it appertains to make and use the same.

My invention relates to coupler operating mechanism whereby the trainman while standing in a safe place may readily shift the car coupler laterally to any position required to permit it to couple with the coupler of an adjacent car. The mechanism for effecting this purpose is preferably also designed to be capable of actuating the coupler locking mechanism to cause it to assume an unlocked position.

Generally stated, the principal features of the invention involve the provision of a lever device forming a part both of the means for shifting the coupler laterally and of the means for actuating the coupler locking mechanism, the car being provided with fulcrum means affording a plurality of fulcrum points with which the lever device may selectively engage, and the fulcrum means and lever device normally occupying an operative relation permitting immediate lateral shifting of the coupler and the instant operation of its locking mechanism.

In the drawings chosen for the purpose of illustrating the invention, the scope whereof is pointed out in the claims,—

Figure 1 is a front elevation of a laterally movable car coupler and coupler operating mechanism constructed in accordance with the invention, the parts being in normal relation corresponding to a central position of the coupler and the locked position of its knuckle locking mechanism.

Figure 2 is a detail side elevation illustrating the preferred mode of connecting the coupler operating mechanism to the coupler.

Figure 3 is a detail side elevation of the coupler operating mechanism.

Figure 4 is a detail view, partly in front elevation and partly in vertical section, of the coupler operating mechanism.

Figure 5 is a detail view in front eleva-

tion illustrating the relation of the parts when the coupler operating mechanism is employed for shifting the coupler laterally, and showing in dotted lines the relation of the parts when the lever device has been transferred to a new fulcrum point in order to facilitate shifting of the coupler to its extreme position of lateral displacement.

Figure 6 is a detail section on the line 6—6, Fig. 4.

In the drawings, 1 indicates the coupler, which, as usual, is provided with a pivoted knuckle and suitable locking mechanism for normally retaining the knuckle in coupled position. The form of coupler, which has been chosen for purposes of illustration merely, is well known and is designed to be mounted upon a railway car so as to be capable of extended lateral swinging movements to either side of its normal or central position. The locking mechanism of the coupler is caused to assume an unlocked position by the operation of a pivoted lock lifter 2 whose outer end is pivotally secured to a link 3 that extends into the coupler head and is operatively connected to the coupler lock. At its rear end the lifter 2 is provided with oppositely disposed horizontal trunnions 4 which are journaled in upwardly opening bearings formed in a bracket 5 rigidly attached to the under side of the coupler. Below the trunnions 4 the lock lifter 2 is fashioned with an opening or recess 6 into which the upwardly extending ends of rotatable operating rods 7 extend. These details of construction are well known to those skilled in the art.

Each of the rods 7 is connected at its outer end to a lever device by means of which the trainman may cause the rod either to rotate to effect an unlocking of the coupler or to be shifted bodily transversely of the car so as to cause a corresponding lateral displacement of the coupler. As both of the lever mechanisms by which the rods 7 are manipulated are of the same construction and operate in precisely the same manner, but one of said devices has been illustrated in the drawings; and it will be apparent that a single unit consisting of one rod 7 and its associated lever device may be employed if desired. Upon rotating either of the rods 7 in the proper direction the pivoted lock lifter

2 will swing upwardly and cause the link 3, which is connected to the coupler lock to move the latter to unlocked position. Where the coupler is equipped with knuckle opening mechanism an extended unlocking rotation 5 of the rod 7 and the lifter 2 will cause the knuckle of the coupler to be thrown to open position. Upon a bodily lateral shifting of either of the rods 7 the coupler 1 will be 10 caused to execute a corresponding lateral displacement, since this transverse movement of the rod is communicated to the coupler through the bracket 5.

Each rod 7 is movably attached at its outer 15 end to the handle member 8 of the lever device with which it is associated. To effect this connection the outer end of the rod 7 may be formed with a perforated eye 9 which is adapted to enter a recess 10 in the said member 8, a rivet 11, which passes through 20 the lever member and through the eye 9, preferably being employed for securely pivoting the rod 7 to the lever device.

The lever device comprises two pivotally 25 connected members the lower one, 8, being formed as a handle which the trainman may grasp, and the upper member 12 being pivotally suspended from a bracket 13 by means of a pivot bolt 14. The member 12 of the 30 lever device is preferably provided at its lower end with perforated arms or jaws 15 between which the upper end of the handle member 8 projects and which serve to cause both the parts 8 and 12 of the lever device to 35 function as a rigid unit when fulcruming upon the bracket 13 in the operation of shifting the coupler laterally. A pivot bolt 16 which passes through the jaws 15 and through the upper end of the handle member 40 8 serves to connect these parts in a manner permitting the handle portion of the lever device to be rotated independently of the member 12. The upper end of the member 12 is preferably provided with a pair of 45 spaced arms 17 which embrace the lower portion of the bracket 13 and through which the pivot bolt 14 passes. By this means the upper member of the lever device is prevented from rotating longitudinally of the car when the handle member 8 is actuated 50 in the operation of unlocking the coupler.

The bracket 13 which may conveniently 55 be secured to the car by means of bolts 18, is preferably formed with a transversely extending rack portion 19 which affords a plurality of fulcrum points with which the pivot bolt 14 of the lever device may selectively engage. In the form of bracket shown in the drawings the rack portion 19 is provided 60 with upwardly extending spaced teeth or projections 20 which, together with the side bars 21 of the bracket, afford three recesses 22 in any one of which the pivot bolt 14 is adapted to be entered. The side bars 13 of 65 the bracket space the rack bar 19 away from

the plate 23 through which the bolts 8 pass a sufficient distance to allow the lever device to be raised so that its pivot bolt 14 may be transferred from one to another of the recesses 22.

If desired the rear upper corner 24 of the handle member 8 may be made square or angular so that by the engagement of the flattened portion of the upper end of said handle member with the portion 25 of the 75 lever member 12 any substantial rearward swinging of the handle upon the pivot bolt 16 is prevented when the train is in motion.

The lever device is suspended from the bracket 13 and its weight normally causes 80 the pivot bolt 14 to remain in one or the other of the recesses 22. The lever mechanism and its fulcrum or supporting bracket therefore normally occupy an operative position enabling the trainman either to shift 85 the coupler laterally or to actuate the coupler locking mechanism by simply grasping the handle member 8 and pulling or pushing it in the proper direction.

To move the coupler 1 laterally the trainman pulls or pushes upon the handle member 8, as the desired direction of movement of the coupler may dictate. This causes the lever device to rotate as a unit about the pivot bolt 14 and to cause a bodily movement 90 of the connected rod 7 in a direction transversely of the car. If, owing to the angular position assumed by the lever device, the coupler 1 cannot readily be shifted the entire distance by a single pull upon the lever device, the latter is actuated to move the coupler for a portion of the distance and then is manipulated to transfer its pivot bolt 14 to another recess 22 enabling the trainman 100 more favorably to apply power to the 105 coupler. Such a transfer of the lever device to a new fulcruming point is illustrated in dotted lines in Fig. 5.

When it is desired to unlock the coupler in any position it may occupy it is only necessary for the trainman to grasp the handle member 8 and pull its lower end toward the outer end of the car. This causes the handle member to rotate upon the pivot bolt 16 and effect a corresponding rotation of the associated rod 7, thereby swinging the lock lifter 2 upwardly and effecting an unlocking of the coupler.

I claim:—

1. In mechanism of the character indicated, 120 the combination with a laterally movable car coupler, of means for shifting said coupler laterally, said means involving a lever device, means operatively connecting said lever device and coupler, and a fulcrum for 125 said lever device rigidly mounted on the car, said fulcrum affording a plurality of fulcrum points with any of which said lever device may selectively engage to shift said coupler laterally in either direction, and said 130

lever device and fulcrum normally being in interengaging relation for effecting lateral shifting of said coupler.

2. In mechanism of the character indicated, the combination with a laterally movable car coupler, of means for shifting said coupler laterally, said means involving a lever device and fulcrum means affording a plurality of fulcrum points with any of which said lever device is adapted selectively to engage to shift said coupler laterally in either direction, said lever device normally being in fulcruming relation with one of said fulcrum points to enable lateral shifting of said coupler by said lever.

3. In mechanism of the character indicated, the combination with a laterally movable car coupler and its locking mechanism, of a lever device, means for operatively connecting said lever device and coupler, and fulcrum means affording a plurality of fulcrum points with any of which said lever is adapted selectively to engage to shift said coupler laterally in either direction, said lever device through its said operative connection with the coupler being adapted to shift said coupler laterally and to unlock said coupler, and being normally in operative position both for effecting the lateral shifting of said coupler and for unlocking the same.

4. In mechanism of the character indicated, the combination with a laterally movable car coupler and its locking mechanism, of means for shifting said coupler laterally, said means involving a lever device comprising a plurality of movably connected members, a rod operatively connected to one of the members of said lever device and to said coupler and adapted to actuate the locking mechanism of said coupler, and fulcrum means adapted to be rigidly attached to a car and serving to support said lever device, said fulcrum means affording a plurality of fulcrum points with which said lever device is adapted selectively to engage, and said lever device and fulcrum means normally being in operative relation for effecting lateral shifting of said coupler.

5. In mechanism of the character indicated, the combination with a laterally movable car coupler, of means for shifting said coupler laterally, said means involving a lever device, means operatively connecting said lever device and coupler, and support-

ing means for said lever device adapted to be rigidly attached to the car upon which said coupler is mounted, said supporting means and lever device being adapted to have selective pivotal engagement at a plurality of points and normally being in operative relation for effecting lateral shifting of said coupler.

6. In mechanism of the character indicated, the combination with a laterally movable coupler and its locking mechanism, of means for shifting said coupler laterally, means for actuating said coupler locking mechanism, the said means for shifting said coupler and for actuating its locking mechanism involving in common a lever device, and a bracket affording a plurality of fulcrum points with which said lever device may selectively engage, said bracket and lever device normally being in operative relation for effecting lateral shifting of said coupler.

7. In mechanism of the character indicated, the combination with a laterally movable coupler, of a bracket adapted to be rigidly attached to a car, said bracket being provided with a plurality of recesses, a lever device pivotally supported by said bracket and adapted to have selective engagement with said bar in said recesses, and means for operatively connecting said lever device and coupler, said lever device comprising a plurality of pivotally connected members one of which is adapted to be moved independently of the other, and said lever device and bracket normally being in operative relation for effecting lateral shifting of the coupler.

8. In mechanism of the character indicated, the combination with a laterally movable car coupler and its locking mechanism, of means for shifting said coupler laterally, and means for actuating said coupler locking mechanism, the said means for shifting said coupler and for actuating its locking mechanism involving in common a lever device, and means for pivotally connecting said lever device to a car, said lever device comprising a plurality of pivotally connected members and being provided with means for limiting rearward rotation of one of said lever members with respect to the lever member to which it is pivotally connected.

In testimony whereof I affix my signature. 110

ENOCH GEORGE, JR.
